HOSE NOZZLE

James A. Jensen, Philadelphia, Pa., assignor to
Quaker City Iron Works, Philadelphia, Pa., a
corporation of Pennsylvania

Application June 22, 1933. Serial No. 677,036

3 Claims. (Cl. 221—100)

This invention relates to hose nozzles; and it has reference more particularly to nozzles for the drain hoses of vehicles used in delivering gasoline oils and other liquid commodities.

When unloading gasoline, for example, from the delivery vehicle, a nozzle is attached to the end of the drain hose and inserted into the inlet pipe of the underground tank at the gas filling or service station where delivery is being made. In order that unloading may be accomplished in a minimum of time, it is requisite that the bore of the nozzle tip be equal to that of the drain hose, and this is the type of nozzle which it is therefore most advantageous to use. However, in a great many service stations, the tanks are fitted with small inlets which vary in diameter and which will not receive the large nozzle tip on the drain hose. In such instances, the nozzle is ordinarily bushed down by means of pipe reducers and a tip of smaller diameter is applied to suit the inlet of the particular tank which is to be charged. The making of such changes is time consuming, troublesome due to difficulty in securing fluid tight joints, and moreover entails the use of wrenches and other tools. As a consequence, the truck drivers will invariably use only the smallest size tip because it can be universally employed, since the time lost in unloading under these conditions is probably no more than that required to make nozzle substitutions as aforesaid.

My invention is directed in the main toward overcoming the several drawbacks which have been mentioned, through provision of a nozzle with interchangeable tips of different sizes capable of being quickly and easily attached and detached by hand without necessitating the aid of wrenches or other tools for the purpose.

Other objects and attendant advantages of this invention will be manifest from the following detailed description of the accompanying drawing, wherein, Fig. I is a fragmentary view partly in elevation and partly in section showing my improved hose nozzle.

Figs. II and III show different interchangeable tips for the nozzle.

With reference first to Fig. I of these illustrations, the numeral 10 designates a flexible drain hose such as is used in connection with gasoline or oil delivery vehicles; while 11 indicates the nozzle with which the present invention is more especially concerned. As shown, the nozzle 11 comprises a hollow body member having, in this instance, the form of an elbow 12 which screws onto the threaded nipple 13 of a terminal fitting 14 at the end of the hose 10. A washer indicated

at 15 serves to render the juncture between the elbow 12 and the fitting 14 fluid tight. The discharge end of the elbow 12 it will be noted, is somewhat enlarged diametrically as at 16 and formed with an internal screw thread 17 of relatively coarse pitch. This thread 17 extends up to a shoulder 18 beyond which there is an annular channel 19, which with said shoulder jointly form a retaining groove to receive the circumferential flange of a circular gasket 20, of rectangular or L-shaped cross-section, whereof the opening corresponds in diameter to that of the flow passage 21 through the elbow 12 and makes a flush surface therewith when compressed as shown in Fig. I; it being readily understood that the bore of said gasket is initially slightly greater than that of the flow passage 21, while the portion thereof engaging the shoulder 18 extends outwardly therebeyond, as indicated at 20' to insure such compression. In practice the gasket 20 is made from a relatively soft resilient material which yields readily to compression and which is resistive to erosion by gasoline or oils.

For interchangeable use with the body member or elbow 12 of the nozzle 11, I have provided a number of nozzle tips, three being shown for convenience of illustration, the same being respectively designated by the reference characters 22, 22a and 22b in Figs. I, II and III. Except for having tubular prolongations 23, 23a and 23b of different diameters and for a slight modification hereinafter referred to, the tips 23a and 23b are of the same construction as the tip 23 so that the description of the latter will, in general, hold for them all. Referring again to Fig. I it will be observed that the prolongation 23 of the tip 22 is formed from tubing preferably of high strength alloy bronze, the upper end of the tube being set into a collar 24 which has a coarse pitch external screw thread 25 to fit the thread 17 in the elbow discharge enlargement 16. In order to secure the tube 23 permanently to the collar 24 it is circumferentially expanded as at 26 into an internal groove of said collar; and after assembling of the parts in this manner, the tube 23 is soldered or welded to the collar 24 around the bottom edge of the latter as at 27. The tip of Fig. I has a bore 28 corresponding exactly to that of the passage 21 through the elbow 12.

The substitutable nozzle tips 22a and 22b on the other hand have bores 28a and 28b smaller than those of the tip 22, and in order to promote smooth fluid flow through them, mergent roundings are formed interiorly of the collars 24a and 24b as at 29a, 29b to render the bores of said tubes 110

continuous with the passage 21 through the elbow. The threads 25a and 25b of the collars 24a, 24b on the tips 23a and 23b are of course made to fit the internal thread 17 of the elbow 12.

5 By virtue of the coarse pitch screw threads 25, 25a and 25b, the tips 22, 22a and 22b are obviously quickly attachable and detachable to and from the elbow 12 so that the adaptation of the nozzle 11 to tank filling openings of different sizes is accomplished in a minimum of time. In attaching the tips 22, 22a and 22b, their collars 24, 24a and 24b are screwed into the elbow 12 until their top ends engage the shoulder 18 within said elbow. The shoulder 18 thus acts as a stop to limit the extent to which the gasket 20 may be compressed and thus prevents undue distortion such as would tend to dislodge said gasket from its retaining groove. Due to the softness of the gasket 20, the screwing up of the tips 22, 22a and 22b, may be effected by hand with assurance of a fluid tight juncture between the parts. Accordingly no tools are required in changing my improved nozzle 11 to suit all conditions imposed in practice.

Having thus described my invention, I claim:

25. 1. A hose nozzle comprising an elbow having one end adapted for coupling connection to the hose.

30. 2. The combination of claim 1 wherein the tip tubing is circumferentially expanded into an internal groove of the attaching collar and said parts are permanently united together.

35. 3. The combination of claim 1 wherein the bore of the attaching collar is mercifully rounded to accommodate tubing of smaller bore.

JAMES A. JENSEN.

and its other end enlarged and provided with an internal coarse-pitched screw-thread extending up to a shoulder therein beyond which is formed an annular channel, said shoulder and channel jointly defining a retaining groove of rectangular cross-section, a similarly-sectioned annular gasket seated in said retaining groove and having a bore slightly greater than that of the flow passage through the elbow with that portion thereof engaging the shoulder aforesaid projecting outwardly therebeyond, and a tip formed of thin tubing with an attaching collar at one end externally screw-threaded to fit into the elbow discharge end as far as permitted by the shoulder therein with incidental limited compression of the annular gasket to provide a fluid-tight seal and safeguarding said gasket against dislodgment from the retaining groove.

2. The combination of claim 1 wherein the tip tubing is circumferentially expanded into an internal groove of the attaching collar and said parts are permanently united together.

3. The combination of claim 1 wherein the bore of the attaching collar is mercifully rounded to accommodate tubing of smaller bore.
